UNITED STATES PATENT OFFICE.

THEODORE W. BURGER, OF DUNELLEN, NEW JERSEY, ASSIGNOR TO BURGER & LEE, OF NEW YORK, N. Y.

DESIGN FOR A GAS OR OIL STOVE.

SPECIFICATION forming part of Design No. 18,945, dated March 5, 1889.

Application filed July 5, 1888. Serial No. 279,122. Term of patent 14 years.

To all whom it may concern:

Be it known that I, THEODORE W. BURGER, of Dunellen, in the county of Middlesex and State of New Jersey, have invented and produced a new and original Design for a Gas or Oil Stove; and the following is declared to be a full, clear, and exact description thereof, reference being had to the accompanying drawings, in which—

10 Figure 1 is a side elevation of a single stove of my design, and Fig. 2 is a side elevation of a double stove of my design.

This design relates to an oil or gas stove that is either round in its horizontal configuration in the single stove, Fig. 1, or elliptical in the double stove, Fig. 2, in both of which there is an ornamental top, A, base B, and body C, the leading feature of the design being the rows of ornamental openings in the 20 annular body C.

The feature of the top A consists of an outwardly-inclined and projecting flange having a scalloped edge and a top edge in representation of a battlement. The feature of the base 25 B consists of an outwardly-inclined and projecting flange having a scalloped edge and

shield-shaped openings. The feature of the ornamental body or casing C consists in the parallel rows of star-shaped openings c and the central bead, c', and the beads c² above and 30 below the rows of star-shaped openings c.

The beads c' c² may, in whole or in part, be omitted from the design of the body or casing C without departing from my design.

I claim as my invention—

35

1. In a design for a gas or oil stove, the design of the annular body or casing having parallel rows of star-shaped openings, substantially as shown.

2. The design for a gas or oil stove, the same consisting in the ornamental top A and base B, and the body or casing C, having parallel rows of star-shaped openings, substantially as shown.

In testimony that I claim the foregoing I 45 have hereunto set my hand this 2d day of June, A. D. 1888.

THEODORE W. BURGER.
